ATTORNEY

UNITED STATES PATENT OFFICE.

THOMAS BISHOP, OF NEW BRIGHTON, NEW YORK.

DESIGN FOR A CORN-HOLDER.

SPECIFICATION forming part of Design No. 25,026, dated December 31, 1895.

Application filed August 26, 1895. Serial No. 560,601. Term of patent 3½ years.

To all whom it may concern:

Be it known that I, THOMAS BISHOP, a citizen of the United States, residing at New Brighton, in the county of Richmond and State of New York, have invented and produced a new and original Design for a Corn-Holder, of which the following is a specification, reference being had to the accompanying drawing, forming part thereof, which shows my new design in side perspective.

The leading features of my design consist in the handle A, of a yoke-shaped form having a central loop, and outwardly and upwardly extending arms E E, the outer edges of which are configured or ornamented as shown in the drawing, and each of said ends E is provided with circular disks F, having outwardly-directed prongs H, and upon the other side of the ends is secured a circular disk or plate M, upon which are formed or-

namental figures, as shown in the drawings, the ornamental figure which is used being such as represents the corn-plant, and it will thus be seen that the entire device is regular in form and presents an ornamental and pleasing appearance to the eye.

Having described my new and original design, I claim and desire to secure by Letters Patent—

The design for a corn holder as herein shown and described,

In testimony that I claim the foregoing as my invention I have hereunto signed my name, in the presence of two witnesses, this 23d day of August, 1895.

THOMAS BISHOP.

Witnesses:
C. GERST,
I. RICHARDS.
